UNITED STATES PATENT OFFICE.

DAVID BARATINI, OF MURPHY'S, AND WILLIAM P. STEVENSON, OF DOUGLAS FLAT, CALIFORNIA.

ORE-PULVERIZER.

SPECIFICATION forming part of Letters Patent No. 380,843, dated April 10, 1883.

Application filed October 1, 1887. Serial No. 251,256. (No model.)

To all whom it may concern:

Be it known that we, DAVID BARATINI, of Murphy's, and WILLIAM P. STEVENSON, of Douglas Flat, Calaveras county, State of California, have invented an Improvement in Ore-Pulverizers; and we hereby declare the following to be a full, clear, and exact description of the same.

Our invention relates to that class of ore-pulverizers or rock-crushers in which a rolling weight operates within a rocking mortar; and our invention consists in the constructions and combinations of devices we shall hereinafter fully describe and claim.

15 The object of our invention is to provide a simple, cheap, and effective ore-pulverizer capable of rapid work.

Referring to the accompanying drawings for a more complete explanation of our invention, 20 Figure 1 is a perspective view of our ore-pulverizer. Fig. 2 is a vertical section of same.

A is the frame of the machine, having a bed-plate, *a*, on which the rocking mortar *B* is supported.

25 *C* is the rolling weight resting within the mortar and operating between the parallel sides *a'* of the main frame.

The rocking mortar *B* is made with a convex under surface, and through its center projects 30 downwardly and upwardly a pin, *D*, the lower portion of which is fitted loosely in a socket, *a'*, in the bed-plate *a*, and the upper portion passes into a socket or aperture, *e*, made in the base of the rolling weight, said aperture or 35 socket being made with an upward flare, so as to allow for the rolling movement of the weight, and also permit said weight *C* to rise upon the material under treatment without slipping thereon lengthwise of the trough and 40 so losing its bite upon the material, while the pin, loosely fitting the socket in the bed-plate, allows for the rocking movement of the mortar. The lower portion of the rolling weight has a metal die, *c'*, secured to it, and the inner surface of the rocking mortar is protected by a metal shoe, *b*. The sides and ends of the mortar are provided with the usual screens, *E*.

45 *F* is a pitman which is connected with the top of the rolling weight *C*, said pitman being 50 reciprocated by any suitable means, such as the means here represented by the crank *G*, having pin *g*, with which the pitman is connected. The rolling weight is made of an annular or ring shape, the sides being boarded

up by pieces *H*, so as to inclose the interior, 55 forming a hollow which is filled with rocks or other suitable weights.

The operation of the pulverizer is as follows: The ore is fed into the mortar and the pitman is operated to cause the weight to roll back 60 and forth in the mortar upon its pin *D*, which movement causes the mortar itself to rock, conforming its movement to that of the rolling weight, and the ore is thereby crushed and pulverized between the die of the weight and 65 the shoe of the mortar. By our construction, however, the parts are held in proper position, steadyng them even under the most rapid movement. The parallel sides *a'* of the frame form perfect and effective guides for the 70 weight in its movement, and the construction of the weight itself, of a ring shape, boarded up on each side and filled with rocks, enables us to provide a simple, cheap, and effective crushing-weight.

Having thus described our invention, what we claim as new, and desire to secure by Letters Patent, is—

1. In an ore-pulverizer, a bed-piece and a rocking mortar supported thereby, in combination with a rolling weight operating in the mortar, and having a socket in its base loosely fitting over a pin in the base of the mortar, substantially as herein described.

2. In an ore-pulverizer, a bed-piece, in combination with a rocking mortar supported thereon and having a central pin seated loosely in a socket of the base-piece, and a rolling weight operating in the mortar and having a socket loosely fitted over the pin of the mortar, substantially as herein described.

3. In an ore-pulverizer, a bed-piece and a rocking mortar mounted thereon, and having a pin seated loosely in a socket in the bed-plate, in combination with a rolling weight operating in the mortar and having a socket loosely fitting over the pin of the mortar, and a reciprocating pitman connected with the rolling weight, whereby it is operated, substantially as herein described.

In witness whereof we have hereunto set our hands.

DAVID BARATINI.
WILLIAM P. STEVENSON.
